CLAIM

The ornamental design for a food support for cooking device, as shown and described.

DESCRIPTION

FIG. 1 is a perspective view of a food support for cooking device, showing our new design;

FIG. 2 is a top view of the embodiment shown in FIG. 1; FIG. 3 is a bottom view of the embodiment shown in FIG. 1;

FIG. 4 is a side view of the embodiment shown in FIG. 1; FIG. 5 is another side view of the embodiment shown in FIG. 1;

FIG. 6 is a front view of the embodiment shown in FIG. 1; and,

FIG. 7 is a rear view of the embodiment shown in FIG. 1.

(Continued)

The broken lines in the figures are for environmental purposes only and form no part of the claimed design.

1 Claim, 5 Drawing Sheets
